(63) Continuation of application No. 29/631,413, filed on Dec. 29, 2017, now abandoned.

Primary Examiner — Terry A Wallace(74) Attorney, Agent, or Firm — Fish & Richardson P.C.(51) LOC (12) Cl. 07-01*CLAIM(52) U.S. Cl.

The ornamental design for a cooler, as shown and described.

(58) Field of Classification Search*DESCRIPTION

USPC D7/603–608, 709, 710, 629; D3/283, D3/287, 289, 233, 267, 268, 273, 276, D3/315, 318
 CPC F25D 2331/804; F25D 2331/801; F25D 3/08; B65D 30/08; B65D 30/22; B65D 81/3858; B65D 81/3828; B65D 81/3888; B65D 81/18; B65D 81/3897; B65D 31/04; B65D 53/00; B65D 69/00; B65D 8/18; A45C 11/20; A45C 13/02; A45F 3/02;

FIG. 1 is a perspective view of a cooler showing my new design in a closed position.

FIG. 2 is a top view of the cooler in a closed position.

FIG. 3 is a bottom view of the cooler in a closed position.

FIG. 4 is a front view of the cooler in a closed position.

FIG. 5 is a rear view of the cooler in a closed position.

FIG. 6 is a right side view of the cooler in a closed position.

FIG. 7 is a left side view of the cooler in a closed position; and,

FIG. 8 is a perspective view of the cooler in an opened position.

The inside of the lower body portion of the cooler is unclaimed, surface shading and contour lines in the drawings represent surface and contour and do not illustrate material, surface ornamentations, or surface decoration and the broken lines in the drawings form no part of the claimed design.
